CLAIM

We claim the ornamental design for terminal cap keying feature for a battery pack, as shown and described.

DESCRIPTION

FIG. 1 is a first perspective view of a battery pack with a terminal cap keying feature according to a second embodiment.

FIG. 2 is a second perspective view of the battery pack with the terminal cap keying feature of FIG. 10.

FIG. 3 is a front side view of the battery pack with the terminal cap keying feature of FIG. 10.

FIG. 4 is a first perspective view of a battery pack with a terminal cap keying feature according to a fourth embodiment.

FIG. 5 is a second perspective view of the battery pack with the terminal cap keying feature of FIG. 22; and,

FIG. 6 is a front side view of the battery pack with the terminal cap keying feature of FIG. 22.

The ornamental design which is claimed is shown in solid lines. Any broken lines represent unclaimed subject matter and form no part of the claimed design. Any line in a drawing may provide a boundary line of a claimed design element. A boundary line of a claimed design element may also be defined in an area between lines in a drawing. An element or a subset of any combination of elements in a drawing may form a claimed design.

1 Claim, 6 Drawing Sheets
